[57] CLAIM

The ornamental design for a garden hose fitting, as shown and described.

DESCRIPTION

FIG. 1 is a perspective view showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the garden hose fitting attached to the end of a hose before it is threadably attached to a water spigot.

The broken lines in FIG. 8 are for illustration only and form no part of the instant design.
